ANDREW P. ODHOLM, OF BRIDGEPORT, CONNECTICUT.

Letters Patent No. 87,282, dated February 23, 1869.

IMPROVEMENT IN MOULDING-TOOL.

The Schedule referred to in these Letters Patent and making part of the same.

To all whom it may concern:

Be it known that I, ANDREW P. ODHOLM, of Bridgeport, in the county of Fairfield, and State of Connecticut, have invented a new Improvement in Cutter-Head for Wood-Mouldings; and I do hereby declare the following, when taken in connection with the accompanying drawings, and the letters of reference marked thereon, to be a full, clear, and exact description of the same, and which said drawings constitute part of this specification, and represent, in—

Figure 1, a face or front view of the cutter-head;

Figure 2, a side view; and in

Figure 3, a central section longitudinally through the shaft of the cutter-head.

This invention relates to an improvement in cutting circular or ring-mouldings, that is, circles of wood moulded upon their face, and such as are used for cabinet and other similar purposes, the object being to cut several rings at a time, one from within the other.

One great difficulty experienced in moulding-machines is to form several cutters so that all shall be alike—a difficulty which, in my invention, is entirely overcome; and

My invention consists in the arrangement, upon the cutter-head, of several cutters, each of which is an arc of a circle, wrought upon the surface the reverse of the form to be cut, so that one end being properly ground, forms a cutter to dress the moulding.

To enable others to construct and use my invention, I will fully describe the same, as illustrated in the accompanying drawings.

A is a cutter-head, of any desirable form and construction, fixed upon a hollow shaft, B.

In the said cutter-head are slots C and D, more or less in number, and into the several slots I arrange adjustable tool-holders E, constructed so as to be bound on to the head, and also to grasp and hold the cutter, as seen in fig. 3, and so that the holder may be set anywhere within range of the slot into which it is placed.

In each of the tool-holders is arranged a cutter, F, which are constructed in the following manner:

On a circle of steel, of the proper diameter, I turn or form the face into reverse shape of the moulding to be produced, more clearly seen in fig. 3. Then the ring I cut into several pieces, each piece to form a

cutter. One end of each I grind off so as to leave a cutting-edge, as seen in fig. 1, and place the cutter in the holder, the said cutting-edge in advance, and slightly raised, as seen in fig. 2. Then I arrange in connection with the cutter, either upon the same holder, as represented by the cutters upon the slot D, near the cutting-end, or in the slot in advance of the cutter, as represented at G, fig. 1, which are the spurs for the cutters in the slot C.

In this manner I arrange opposite cutters to traverse in the same line, to dress the same moulding. This I do by preference, as each cutter may dress a separate surface, one outside of the other. Thus four cutters dress four rings.

In practice I find it important to hold the wood to be cut at the centre.

For this purpose I arrange, through the hollow shaft B, a spindle, H, which has upon its inner end a head, I, adjustable axially in the shaft, and this I bring to bear upon the centre of the wood when it is presented to the cutters.

By this construction I am enabled to dress several rings at the same time, in the most perfect manner, and each successive ring exactly like the one preceding it, and the skilled labor heretofore necessary for sharpening the cutters, is avoided, as the most inexpert workman is able to grind the end of the said cutters.

If desirable, cutters of different moulded surfaces may be arranged in the head, so that one ring may be of one form, a second of another, and so on.

Having fully described my invention;

What I claim as new and useful, and desire to secure by Letters Patent, is—

1. The arrangement, in revolving cutter-heads, of the segmental-shaped cutters F F, so that one set of cutters will cut within the circle of another, and all made adjustable in the said head, substantially as and for the purpose set forth.

2. In combination with the above, the supporting-head I, arranged so as to operate substantially as set forth.

ANDREW P. ODHOLM.
